BABY SUPPORT FOR USE IN BATHTUBS

Malcolm I. Davis, Jr., New York, N. Y., assignor of twenty per cent to Barbara B. Davis, New York, N. Y., and twenty per cent to Thomas Wallace, IV, and twenty per cent to Muriel M. Wallace, both of Woodbridge, Conn.

Application February 13, 1947, Serial No. 728,361

5 Claims. (Cl. 4—185)

1

This invention relates to a baby support for use in a bathtub.

One of the objects of this invention is to provide a baby support for use in a bathtub, the primary characteristics of which will be simplicity, practicability, and durability. Another object is to provide a device of the above character which will be neat and attractive in appearance. Another object is to provide a device of the above character which will be strong and well able to withstand continuous, hard usage. Another object is to provide a device of the above character, the manufacture of which will be economical both from the standpoint of labor and materials used. Another object is to provide a device of the above character which may be used in any bathtub having a smooth bottom. Still another object is to provide a device of the above character which may be easily and quickly attached to or removed from a bathtub. A still further object is to provide a secure and safe device of the above character for supporting and holding a baby in a sitting position in a bathtub. Other objects will be in part obvious and in part pointed out hereinafter.

The invention accordingly consists in the features of construction, combinations of elements, and arrangements of parts, all as will be illustratively described herein, and the scope of the application which will be indicated in the following claims.

In the accompanying drawing in which is shown one of the various possible embodiments of this invention,

Figure 1 is a perspective view of the baby support for use in a bathtub;

Figure 2 is a side elevation of the support shown in Figure 1;

Figure 3 is a front elevation of the support shown in Figure 1; and,

Figure 4 is a top plan of the support shown in Figure 1.

Similar reference characters refer to similar parts throughout the several views of the drawing.

As conducive to a clearer understanding of certain features of this invention, it might here be pointed out that certain difficulties have been experienced with devices of this type in the past which are used to support a baby in a bathtub from the age of six months until it is able to support itself. In bathing a baby of this age, if a support is not used, it is necessary to support the baby with one hand while washing the baby with the other. This is awkward and difficult

to do because the baby is wet and slippery and there is always the chance that the baby may slip from the mother's hands with the possibility that the baby may be injured by striking the side or bottom of the bathtub. One of the main difficulties with supports now in use is that their frameworks do not permit ready access to the body of the baby for washing and also prevent a baby from moving freely when it is playing in the bathtub. Furthermore, supports now in use are not securely attached to the bathtub which is dangerous because if a support becomes loose from the bathtub, it may upset and the baby may be injured. Accordingly, it is another object of this invention to provide a baby support for use in a bathtub which affords maximum accessibility to the baby when it is being bathed, permits the baby a maximum of freedom of movement, and is securely attached to the bathtub.

20 Referring now to Figure 1, the support includes a back rest, generally indicated at 10, supported by legs, generally indicated at 12, 13, and 14. Back rest 10 is curved longitudinally to fit the body of the baby, and to make it comfortable and safe, its upper and lower edges 10a and 10b are curved rearwardly. Back rest 10 is secured to an upwardly extending portion 13a (Figure 2) of leg 13 by a pair of rivets 15 and 16 or other suitable means. From portion 13a leg 13 extends rearwardly, curves downwardly, and thence forwardly to form a portion 13b. Portion 13b of leg 13 is secured by nuts 17 and 18 to a pair of bolts, similar to bolt 19 (Figure 3), which are embedded in rubber suction cup 20 and extend through holes (not shown) in portion 13b. Suction cup 20 is preferably of substantial size so that it will securely grip any surface to which it is attached. The particular shape of leg 13 is of importance as the greatest strains are placed upon the support when a baby moves forwardly with respect to back rest 10. By curving the leg 13 downwardly and thence forwardly, all strains resulting from such movement of a baby upon suction cup 20 are substantially in line with the vertical axis of the cup which is the direction in which the cup is able to withstand the greatest strain.

Legs 12 and 14 are the legs of a U-shaped element, the center portion 21 (Figure 3) of which is connected to leg 13 by rivets 22 (Figure 4) or other suitable means. The lower ends of legs 12 and 14 extend outwardly to form portions 12a and 14a by means of which these legs are connected to suction cups 23 and 24 which are similar in construction to cup 20. Portions 12a and 14a have holes therein through which bolts, such as

bolt 19, pass. The heads of these bolts are embedded in suction cups 23 and 24, and the bolts and thus the cups are connected to portions 12a and 14a by nuts 25 and 26.

Portions 12a, 13b, and 14a (Figures 2 and 3) of legs 12, 13, and 14 lie in the same plane, and as cups 20, 23, and 24 are of the same size, the bottoms of the cups all lie in one plane. When the device is mounted on a slightly curved or uneven surface, because of the resiliency of the cups and legs and because the support has three legs which form a tripod, the device adapts itself to the curved or uneven surface, thus permitting the device to be securely attached to such a surface. This is in contrast to a support having four legs, which, if the surface is uneven or if one of the legs is bent, will not before attachment contact the surface with all its cups, and thus, if such a device is secured to such a surface, the support exerts a constant pull upon one of the cups. Thus the provision of three legs upon this support has definite advantages over supports now in use which are attached to a surface at four points.

To secure the baby to back rest 10, a belt 27 is provided. This belt is preferably made of woven cotton and its two ends after passing through slots 29 and 30 in back rest 10, are fastened together behind the back rest. Any suitable device may be used for securing the two ends of the belt together, but the ends are preferably joined by means of a female snap fastener mounted on one end of the belt and a series of male snap fasteners 28 mounted on the other end of the belt at spaced points. Thus, by connecting the female snap to different male snaps, the effective length of the belt may be made to fit the size of the particular baby with which the support is to be used and may be lengthened as the baby grows.

When it is desired to use the support, water is preferably first placed in a bathtub and then the support is mounted on the bottom of the bathtub by pressing downwardly upon legs 12, 13, and 14. Because of their size, suction cups 20, 23, and 24 securely anchor legs 12, 13, and 14 and thus the support to the bottom of the bathtub. If the bottom of the bathtub is curved, the resiliency of the legs and the suction cups, and the fact that the support has three legs, permit the support to be securely fastened to it. After the support is mounted in the bathtub, the baby is placed against back rest 10, belt 27 is drawn tightly around the baby and the ends of the belt are fastened together behind the back rest by the snap fastener. With the baby thus held by the support, a maximum of access to the body of the baby is afforded which is of major importance to a mother bathing a baby. The support also gives the baby complete freedom for kicking, splashing and playing with its toys and at the same time safely and securely supports the baby so that it cannot injure itself.

It will thus be seen that a practical and efficient support for a baby in a bathtub has been disclosed in which the several objects hereinabove mentioned, as well as many others, are successfully accomplished.

As many possible embodiments may be made of the above invention, and as many changes might be made in the embodiment above set forth, it is to be understood that all matter hereinabove set forth or shown in the accompanying drawing is to be interpreted as illustrative and not in a limiting sense.

I claim:

1. In a device for supporting a baby in a bathtub or on any smooth surface, the combination of, a back rest, means for connecting a baby to said back rest, a framework including three legs, means for connecting said back rest to said framework, and a suction cup secured to each of said legs, said legs being in the form of a tripod and being positioned rearwardly of said back rest, the lower faces of said cups being positioned in the same plane, said cups being adapted to secure said framework to the bottom of a bathtub or to any smooth surface.

15 2. In a device for supporting a baby in a bathtub or on any smooth surface, the combination of, a back rest member, a framework member, means for connecting said back rest member to said framework member, three suction cups secured to said framework member, said suction cups being positioned in the form of a triangle rearwardly of said back rest member, the lower faces of said cups being positioned in the same plane, two of said cups being positioned immediately rearwardly of said back rest member and being spaced a substantial distance from each other, the other of said cups being positioned rearwardly of said first-mentioned cups and being aligned with the center of said back rest member, and a belt connected to one of said 20 members for connecting a baby to said member, said cup being adapted to secure said framework member to the bottom of a bathtub or to any smooth surface.

25 3. In a device for supporting a baby in a bathtub or on any smooth surface, the combination of, a longitudinally curved back rest, means for connecting a baby to said back rest, a framework including a U-shaped member and a member extending rearwardly and curving downwardly from the center portion of said U-shaped member, means for connecting said members together, means for connecting said back rest to said framework, and a suction cup connected to the lower ends of each of the legs of said U-shaped 30 member and to the lower end of said second-mentioned member, the lower faces of said cups being positioned in the same plane.

40 4. In a device for supporting and holding a baby in a bathtub or on any smooth surface, the combination of, a longitudinally curved back rest of substantial width, a framework positioned rearwardly of said back rest including a U-shaped member and a member extending rearwardly and curving downwardly from the center portion of 45 said U-shaped member, means for connecting said members together, means for connecting said back rest to said framework, a suction cup connected to the lower ends of each of the legs of said U-shaped member and to the lower end of said second-mentioned member, the lower faces of said cups being positioned in the same plane, means forming a pair of openings adjacent the ends of said back rest, an adjustable flexible belt having its ends extending through said openings, and means for connecting the ends of said belt together behind said back rest.

50 5. In a device for supporting and holding a baby in a bathtub or on any smooth surface, the combination of, a longitudinally curved back rest of substantial width, a framework positioned rearwardly of said back rest including a U-shaped member and a member connected to the center portion of said U-shaped member, said last-mentioned member including a portion extending 55 upwardly behind said back rest, means connect-

ing said portion to said back rest, said last-mentioned member also extending rearwardly from the center portion of said U-shaped member, curving downwardly, and thence extending forwardly, a suction cup mounted on the forwardly extending section of said second-mentioned member, a suction cup mounted on the lower ends of each of the legs of said U-shaped member, the lower faces of said cups being positioned in the same plane, said U-shaped member being transversely positioned with respect to said device immediately rearwardly of said back rest, the cup on said second-mentioned member being positioned rearwardly of the cups on said U-shaped member, and adjustable belt means for connecting a baby to said back rest, said cups being adapted to secure said framework to the bottom of a bathtub or to any smooth surface.
